UNITED STATES PATENT OFFICE.

WILLIAM J. FOSTER, OF HOBOKEN, NEW JERSEY.

SAFETY-GUARD FOR RAILWAY-CARS.

SPECIFICATION forming part of Letters Patent No. 512,181, dated January 2, 1894.

Application filed October 20, 1893. Serial No. 488,669. (No model.)

To all whom it may concern:

Be it known that I, WILLIAM J. FOSTER, of Hoboken, in the county of Hudson and State of New Jersey, have invented a new and useful Improvement in Safety-Guards for Railway-Cars, of which the following is a specification.

My invention relates to an improvement in safety guards for railway cars in which a cradle mounted beneath the platform of the car is arranged to be thrust forward, low down to the ground, under the impulse received by a fender located across the front of a car.

In providing for the safety of individuals and animals crossing the track in front of a cable, trolley or horse car, it is desirable that the safety guard should not extend to any considerable degree in front of the front end of the car where it would be liable to become injured by the wheels of trucks or other vehicles crossing the track in proximity to the car and at the same time it is desirable that there should be some means for catching the body of the person or animal struck by the car, in such a manner as to carry the body along without serious injury until the car can be brought to a full stop.

It is to the accomplishment of the above desired ends that my present invention is directed and it consists, briefly speaking, of a spring actuated, low down cradle, held normally in a housed position beneath the platform of the car and provided with suitable antifriction rollers at its forward end so that it may ride along, when in action, close down to the surface of the track and a yielding fender arranged in an upright position in front of the end of the car and extending down to a point within a few inches of the track, the fender being mounted to move up and down in right lines and so connected with the spring actuated cradle that when the fender comes into contact with an object on the track, it will momentarily yield under the impulse and thereby release the spring actuated cradle which will be promptly thrown forward into position to catch the object struck by the fender.

In the accompanying drawings, Figure 1 is a view of the guard in vertical section lengthwise of the car, showing the parts in their

normal position. Fig. 2 is a view of the same in side elevation, showing the parts thrust forward into the position which they assume immediately after the object has been struck by the fender. Fig. 3 is a top plan view of the car, the platform of the car being removed to show the position of the working parts, and Fig. 4 is a transverse section through the platform of the car on a plane in front of the cradle-supporting hangers.

The spring actuated cradle is denoted by A. It is advantageously formed of curved side rails *a* and one or more intermediate rails of the same shape over which, between the side rails, is stretched a body or floor of woven wire B. Its front edge is provided with a cushion *a'* of rubber or other suitable yielding material and in close proximity to its front edge it is provided with rollers *b* adapted to rest on the surface of the track when the cradle is thrust forward into operative position and I also find it desirable to provide the cradle with supporting rollers *b'* upon which the cradle may rest whenever the weight carried by it in its forward position is sufficient to spring the said rollers *b'* down into contact with the surface of the track.

The rear end of the cradle is pivotally secured to the free ends of arms C, extending laterally from a rock shaft D mounted in suitable bearings underneath the car. The arms C may be conveniently formed by developing the shaft D into cranks at the proper intervals, or the shaft may be made straight and the arms fixed thereto. The shaft D is held under tension tending to rock it to throw the cradle forward, by a spring, in the present instance a stiff band spring E, secured at one end to the under side of the car and extending thence over and around a disk bearing *d* on the shaft, its opposite end being secured to the periphery of the disk bearing. At its outer ends the rock shaft D is provided with a pair of disks *d'* provided on their peripheries each with an abutment *d''*, which may be a tooth, for the purpose of locking the cradle in its position beneath the platform. The front portion of the cradle is held normally above the surface of the ground by means of a pair of hangers F depending from the platform of the car and provided at their lower ends with lips *f* adapt-

ed to take under wings a^2 on the side rails of the cradle, when the cradle is in its normal position, said wings on the rails being adapted to slide off from the lips on the hangers and 5 permit the forward end of the cradle to drop onto the surface of the track whenever the shaft D is released to thrust the cradle forward.

In front of the end of the car a fender G, 10 which may be advantageously made of woven wire supported by a suitable frame work, is suspended; the said fender being hinged to slides g, mounted on vertical guide rods H, secured to the end of the car. The connection 15 is such that the fender G is permitted to swing rearwardly on its hinges a predetermined distance and, at the same time, move vertically on the rods H, while stops g' projecting from the top of the fender above its 20 hinged connection are in position to engage the front of the car and prevent the fender from swinging forwardly beyond a certain position. The ends of the fender are connected by trip rods h with the cradle actuating 25 shaft as follows:—The trip rods h extend rearwardly through suitable guide hangers I and at or near their rear ends they are provided with abutments h', which may be teeth formed thereon, adapted to engage the abutments 30 on the disks on the rock shaft and prevent the latter from rotating so long as the fender is in its advanced or normal position. The trip rods h are further provided with recesses h² which, when the trip rods are forced 35 rearwardly by the slight rearwardly swinging movement of the fender under the impulse of an object struck, will permit the trip rods to drop out of engagement with the abutments on the rock shaft, and the latter will thereby 40 be free to rotate under the tension of its actuating spring.

On the sides of the cradle there are formed abutments a³ against which the lower edge of the fender G will press to lock the cradle in 45 its advanced position.

The practical operation of the device is as follows:—The fender G, hanging normally with its lower edge four inches or less above the surface of the track and the cradle to the 50 rear of the fender in suspended adjustment, whenever the fender strikes an object on the track, the impulse will swing it rearwardly sufficient to trip the rock shaft D and the cradle will be, by the rotation of such shaft, 55 promptly pressed forward underneath the fender and with its front edge riding along the surface of the track so as to catch the object struck by the fender. The fender will lift on its guide rods as the cradle is thrust 60 forward and as soon as the latter reaches the limit of its forward movement, the fender

will fall into position behind the abutments on the sides of the cradle and will thereby lock it securely in its advanced position, forming in effect a chair for the occupancy 65 of the object struck and effectually preventing the object from becoming entangled in the guard operating mechanism or otherwise injured until the car shall have been brought to a stop.

A lever, at all times under the control of the gripman, motorman or driver, and denoted in the present instance by K, may be rocked to swing the fender and release the cradle if its intentional operation on his part 75 shall at any time be found desirable.

It is obvious that slight changes might be resorted to in the form and arrangement of the several parts herein described without departing from the spirit and scope of my invention. Hence I do not wish to limit myself strictly to the construction and arrangement 80 herein set forth, but

What I claim is—

1. The combination with a fender mounted 85 at the end of a car to move up and down in right lines, of a cradle arranged to move forward along the track in a path extending above the plane normally occupied by the movable fender and means for actuating the 90 cradle, substantially as set forth.

2. A safety guard, comprising a movable fender, a cradle having a traveling movement from a point to the rear of the fender to a position in front of the fender, a spring actuated rock shaft connected with the cradle to advance it and a trip rod connected with the swinging fender and having an engagement with the rock shaft to lock and release it, substantially as set forth.

3. A safety guard, comprising a movable fender, a cradle free to move from a position to the rear of the fender to a position in front of the fender, supports for holding the cradle suspended at its front edge when in normal 105 position, a spring actuated rock shaft engaged with the cradle at its rear edge to advance it, and a trip mechanism under the control of the movable fender to release the rock shaft, substantially as set forth.

4. A safety guard, comprising a vertically movable fender, a cradle free to move beneath the fender and means for actuating the cradle, the vertically movable fender having an interlocking engagement with the cradle 115 to hold it in its advanced position, substantially as set forth.

WILLIAM J. FOSTER.
